CLAIM

The ornamental design for a cantilevered stop pin vise stop, as shown and described.

DESCRIPTION

This CPA (continued prosecution application) claims the benefit of the priority date of pending and earlier filed U.S. Design patent application Ser. No. 29/515,783 filed Jan. 27, 2015. "Where the conditions of 35 U.S.C. 120 are met, a design application may be considered a continuing application of an earlier utility application." See MPEP Section 1504.20.

FIG. 1 is a top left perspective view of a cantilevered stop pin vise stop showing my new design;

FIG. 2 is a left side elevational view thereof, a right side elevational view being identical;

FIG. 3 is a top plan view thereof;

FIG. 4 is a bottom plan view thereof;

FIG. 5 is a front elevational view thereof; and,

FIG. 6 is a rear elevational view thereof.

The broken line showing of parts of the drawings is included for the purpose of illustrating use and environment and forms no part of the claimed design.
